UNITED STATES PATENT OFFICE

LOUIS A. VON TILL, OF BROOKLYN, NEW YORK, ASSIGNOR TO ANCHOR CAP & CLOSURE CORPORATION, OF LONG ISLAND CITY, NEW YORK, A CORPORATION OF NEW YORK

DESIGN FOR A CLOSURE CAP OR SIMILAR ARTICLE

Application filed August 21, 1931. Serial No. 40,897. Term of patent 14 years.

To all whom it may concern:

Be it known that I, LOUIS A. VON TILL, a citizen of the United States, residing at Brooklyn, county of Kings, State of New York, have invented a new, original, and ornamental Design for a Closure Cap or Similar Article, of which the following is a specification, reference being had to the accompanying drawing, forming a part there-of.

The figure is a perspective view of a closure cap, showing my new design.

I claim:

The ornamental design for a closure cap or similar article, substantially as shown.

In witness whereof, I have hereunto affixed my hand this 19th day of August, 1931.

LOUIS A. VON TILL.
